UNITED STATES PATENT OFFICE.

NORTON WAGNER, OF SCRANTON, PENNSYLVANIA.

INK-FOUNTAIN.

No. 901,760.

Specification of Letters Patent.

Patented Oct. 20, 1908.

Application filed October 4, 1906. Serial No. 337,386.

To all whom it may concern:

Be it known that I, NORTON WAGNER, a citizen of the United States, residing at Scranton, in the county of Lackawanna and State of Pennsylvania, have invented certain new and useful Improvements in Ink-Fountains, of which the following is a specification.

My invention comprises improvements in ink fountains for printing presses, the details and advantages of which will be clear from the following specification, taken in connection with the accompanying drawing, in which,

Figure 1 is a top plan view of the ink fountain, and the supporting arm for connecting it to the press; Fig. 2 is a side elevation of the same; Fig. 3 is a central vertical section taken longitudinally through the fountain; Fig. 4 is a side view, partly in section, of a portion of the lever for operating the feed roller, showing the pawl and ratchet wheel; Fig. 5 is a side view of the screw for retaining and locking the adjusting screw; and Fig. 6 is a vertical section on the line 6—6 of Fig. 1, and Fig. 7 is a perspective view of a wedge-shaped washer for adjusting the level of the ink fountain.

Referring to the drawing, A indicates the ink fountain, B the supporting arm for attaching it to a printing press, C the rotatable ink plate or disk of the press, and D the usual bracket on the press for supporting the disk.

The ink fountain comprises an outer rectangular metal box or casing a, open at the top, and having a feed roller b fitting between the sides 1 and 2 at one end of the casing and closing said end. This roller is mounted upon a shaft c which extends through and is journaled in the sides of the casing, at their ends. Within the casing a is arranged a sliding ink trough d having sides 3 and 4 parallel with the sides 1 and 2 respectively, and fitting closely against the sides of the roller at their forward ends, as shown in Fig. 1. The bottom 5 of the trough slopes from the rear, or left hand end in the drawing, toward the roller, and the forward end 5^a of the bottom of the trough is concave, as shown, to fit the convex surface of the roller. The sides 1 and 2 of the outer casing extend beyond the bottom 6 of the casing leaving an opening between the roller and the forward end of the bottom 6. The forward end of the bottom

of the trough d rests upon the forward end of the bottom 6, as shown in Fig. 3. The trough d is adjustable toward and from the roller by means of an adjusting screw e which is threaded into a lug 7 on the under side of the bottom of the trough. This adjusting screw extends through a vertical slot 8 in the rear end of the outer casing and has a shoulder 9 which abuts against the casing.

The adjusting screw e has an annular groove 10, and a screw E, Figs. 1, 3, and 5, extends across the rear end of the casing above the adjusting screw and has a reduced end or pintle 11 which fits within the annular groove and normally prevents the adjusting screw from being moved upwardly out of the slot 8. The retaining screw E also has a tapered portion 12 which, when the screw is turned inwardly to its full extent, binds against the adjusting screw e and locks the latter against turning. By loosening the screw E the adjusting screw e may be turned to adjust the trough toward or from the roller and thus adjust the width of the opening between the curved end 5^a of the bottom of the trough and the face of the roller so as to permit more or less ink to be fed out of the trough on the face of the roller when the latter is rotated.

The ink fountain is supported upon the arm B by means of a yoke F bolted to said arm and connected to the ink fountain by a pivot pin 13 which passes through the sides 90 of the outer casing beneath the bottom 6. The forward end of the ink fountain rests upon an adjusting screw G which is threaded into the supporting arm B, the arrangement being such that by adjusting the screw G 95 the roller b may be raised or lowered relative to the ink disk C, and the forward end of the ink fountain may swing upwardly about its pivotal support 13.

The shaft c has a key-way 14 extending 100 throughout its length, and the roller has a spline or key 15 integral therewith which fits within the key-way so that the shaft and roller turn together. A ratchet wheel H is also fitted upon the shaft and provided with 105 an integral key or spline 16 which fits within the key-way 14. This ratchet wheel is arranged within a vertical slot 17 in a lever I, and a pawl 18 pivoted between the walls of said slot is adapted to engage the teeth of the 110 ratchet wheel. One arm 19 of the lever I is made heavy enough to rock the arm in one

direction by gravity, and the opposite arm 20 of the lever has connected thereto a chain 21 by which the lever may be attached to a reciprocating part of the printing press so 5 that the arm will rock in the direction to feed ink by movement of the part of the press to which the chain is attached, and will move in the opposite direction by reason of the weighted arm 19.

10 It will be noted that by providing the roller and ratchet wheel with splines or keys which fit within the groove or key-way in the shaft the lever, ratchet wheel, roller, and shaft may all be readily taken apart by re- 15 moving the cotter-pin 20 from the end of the shaft, and may be as readily assembled. It is desirable to have the parts readily removable for the purpose of cleaning the fountain, which is necessary from time to time in 20 practice and particularly when an ink of a different color is to be placed in the fountain. It will also be noted that by providing the key-way in the shaft and the integral keys within the ratchet wheel and roller there is 25 nothing upon the shaft to interfere with the insertion of the shaft through the circular openings or bearings in the side walls of the outer casing and in the walls of the slot in the lever. The trough *d* also may be readily 30 removed by unscrewing the retaining and locking screw *E* so that the adjusting screw *e* may be moved vertically upward through the slot 8, and the trough and adjusting screw may be lifted out of the outer casing 35 for the purpose of cleaning the trough and casing. By having the parts made so that they can be readily removed or taken apart much time is saved in cleaning the fountain.

A stop 22 is arranged upon the side 2 of 40 the casing, and stops 23 and 24 upon the lever *I* cooperate with the stop 22 to limit the movement of the lever. The normal position of the lever is shown in full lines in Fig. 2, and the dotted lines indicate the position of the lever when the arm 20 is pulled 45 downward to its full extent by the chain 21. Each time an impression is taken on the press, the lever is moved from the position shown in full lines to that shown in dotted lines, moving the feed roller a definite extent. 50 By throwing the pawl 18 out of engagement with the ratchet wheel *H* the feed of the roller may be stopped without stopping the press or disengaging the chain from the press.

The arm *B* is provided with a suitable number of bolt holes 25, so that the fountain can be set approximately in the proper position relatively to the ink disk and ink or 60 form roller, by means of the bolt 26 passing through one of said bolt holes and into the post or bracket *D*, and the finer adjustment of the fountain is effected by setting the screw 27, connected with the yoke *F*, at the 65 proper position within the slot 28 in the end

of the arm *B*. A wedge-shaped washer *K* (Figs. 2 and 7) is placed between the yoke *F* and the arm *B*, upon the screw 27, and by turning this washer to the correct position the axis of the ink roller may be tilted 70 so as to bring it parallel with the axis of the ink or form roller.

When in proper position upon the press, the form roller will engage the feed roller and receive its supply of ink without disturbing the position of the fountain. In 75 some presses the ink or form rollers travel higher on the ink disk when the impression is off than when on, and in such case the form roller will pass under the feed roller, 80 and the fountain will be moved upward off of the supporting screw *G*. In order to prevent injury to the composition form roller, when this occurs, the under side of the outer casing of the ink-fountain is made 85 concave, as indicated at 29, so that the roller will not be torn by the casing, and I also provide a shoe or guard *J* upon one side of the casing which will be engaged by the pulley or trunnion at the end of the form 90 roller, so that the ink fountain will be raised by the trunnion or pulley, engaging the shoe, instead of by the composition roller. This shoe, as shown in Fig. 2, is detachably 95 connected to the side of the outer casing of the fountain by screws 30, passing through a longitudinal slot 31 in the shoe, permitting longitudinal adjustment of the shoe, and the arm 32 extends to the forward end of the outer casing, below the bottom of the casing, 100 and into position to be engaged by the pulley or trunnion of the form roller.

What I claim is,—

1. An ink fountain comprising an outer casing having a vertical slot at one end, a feed roller arranged at the opposite end of the casing between its sides, an ink trough within the casing, an adjusting screw extending through said slot and engaging the trough, and a locking screw threaded into the casing above the adjusting screw and transversely thereto, said locking screw being adapted to retain the adjusting screw within the slot and having a tapering part adapted to bind against the adjusting screw. 105

2. An ink fountain comprising an outer casing having a vertical slot at one end, a feed roller arranged at the opposite end of the casing between its sides, an ink trough within the casing, an adjusting screw extending through said slot and engaging the trough, said adjusting screw having an annular groove, and a locking screw threaded into the casing above the adjusting screw and transversely thereto, said locking screw having a part adapted to fit loosely within the groove in one position of the locking screw and having a tapering part adapted 110 to bind against the adjusting screw in another position of the locking screw. 115

3. The combination with a suitable supporting arm, of an ink fountain, a device for connecting said fountain pivotally to the arm, and a wedge-shaped washer between 5 said device and arm, for the purpose set forth.

4. An ink fountain comprising an outer casing pivotally supported at its rear end, a feed roller at the forward end of the casing, and a shoe secured to the casing and extending at one side of the roller below its 10 axis, for the purpose set forth.

5. An ink fountain comprising an outer casing pivotally supported at its rear end, a feed roller at the forward end of the casing, and a shoe secured to the casing at one side 15 of the roller, said shoe being adjustable longitudinally of the casing.

6. An ink fountain comprising an outer casing pivotally supported at its rear end and a feed roller at the forward end of the 20

casing, the under side of said casing being concave adjacent to the roller, and a shoe secured to the casing and extending at one side of the roller.

7. An ink fountain comprising an outer casing having a vertical slot at one end, a feed roller arranged at the opposite end of the casing between its sides, an ink trough within the casing, an adjusting screw extending through said slot and engaging the trough, said adjusting screw having an annular groove, and a threaded locking device extending over the screw and fitting into 25 said annular groove.

In testimony whereof I affix my signature, in presence of two witnesses.

NORTON WAGNER.
